P. Burkhardt

Inventor:
Bertie S. Harrington,
By Cromwell, Christ & Ward, Atty.

UNITED STATES PATENT OFFICE

BERTIE S. HARRINGTON, OF FORT WORTH, TEXAS

FILLING MACHINE GOVERNOR

Application filed July 5, 1927. Serial No. 203,307.

This invention has to do with automatic measuring and dispensing machines of the volumetric type disclosed in my earlier Patent, No. 1,555,008.

5 The principal object of the invention is to provide a governor for such machines which will cause the lard or other substance being dispensed to attain a certain predetermined pressure before leaving the machine, whereby 10 to insure absolutely correct measurement and prevent streaking such as occurs if the pressure is allowed to fluctuate.

Another important object is to provide a 15 governor for such machines which will cause the substance to pass around the machine and back to the source of supply should the machine discontinue operation for any reason without the flow of substance to the machine being discontinued at the same time.

20 Still other objects and advantages of the invention will be evident upon a full understanding of the construction and operation of the governor.

One form of the invention is presented here- 25 in for the purpose of exemplification, but it will of course be appreciated that the invention is susceptible of embodiment in other structurally modified forms coming equally within the scope of the claims.

30 In the drawing:

Fig. 1 is a side view of a machine equipped with the governor of the invention;

Fig. 2 is an end view of the upper portion of the machine; and

35 Fig. 3 is a vertical section through the governor, the portion above the broken lines being taken at right angles to the portion below the same.

The machine used in the drawing to illustrate one application of the new governor is 40 quite similar in construction and operation to the machine disclosed in my earlier patent above referred to, and therefore will not be described in as much detail as would otherwise be necessary.

Briefly, the machine includes a measuring cylinder which fills and empties itself. A floating piston is positioned in the cylinder between two ports. The ports are connected 45 by valves with two discharge nozzles and with

two branches of a pipe containing the substance under pressure to be dispensed. The valves are so synchronized that when one of the ports is placed in communication with one of the discharge nozzles, the other of the ports 55 is placed in communication with one of the branches of the supply pipe, and vice versa, the pressure on the substance entering the cylinder through one of the ports moving the piston toward the other of the ports and 60 ejecting through that port the substance which, during the preceding stroke of the piston, had entered the cylinder through that port. The valves are operated by an air motor which is connected with a pipe containing air under pressure, and the motor is actuated every time that the piston completes a stroke by suitable control mechanism. 65

The governor which forms the subject matter of the invention prevents the air motor 70 from operating the valves until after the pressure on the substance in the supply pipe and in the cylinder has reached a predetermined amount, with the result that every 75 unit of the substance leaving the cylinder through the discharge nozzle is the same not only in volume but in pressure.

The governor shown in the drawing consists of an upright casing 10 having a bore 11 in which a hollow piston 12 is slidably mounted. The lower end of the piston 12 is closed and is provided with a reduced portion 13 which extends into and seats against the bottom of a transverse passageway 14 located near the bottom of the casing. The reduced portion 13 prevents the piston 12 from closing off the passageway 14. When the governor is connected up with the machine, the passageway 14 forms a section of the supply 80 line 15 through which the substance to be dispensed is fed under pressure to the machine. The upper end of the piston 12 is open except for a perforated cross web 16. A rod 17 is mounted in the web 16 and extends upwardly 85 through a chamber 18 into a closely fitting bore 19.

A transverse passageway 20 is located near the top of the casing, and, when the governor is connected up with the machine, such 90 passageway forms a section of the air line 100

21 through which air under pressure is conducted to or from the air motor operating the valves of the machine. When the piston 12 and the rod 17 are in the positions shown in Fig. 3, the rod 17 effectively closes off the 5 passageway 20 and prevents the air motor from operating, but when the pressure in the supply line 15 builds up sufficiently, it causes the piston 12 to be lifted in the bore 11 until a reduced portion 22 of the rod 17 in the bore 10 19 is moved into a position in register with the passageway 20 in the casing, whereupon the air line 21 is opened up and the machine is permitted to discharge a unit of the substance. 15 From this it will be understood that the rod 17 must move upwardly before a unit can be discharged. Between discharges, the rod moves downwardly again.

The pressure on the substance within the 20 supply line 15 acts against the pressure on the air contained both within the hollow piston 12 and the chamber 18, and the particular pressure at which the governor will open up the air line 21 is determined by the setting of an adjustable pressure relief device 23 of any well known construction, the device 23 being connected with the chamber 18 by a conduit 24.

The air in the piston 12 and chamber 18 is 30 prevented from working down into the substance in the supply line by the provision of a flanged packing 25 in the bore 11, and the substance in the supply line is prevented from working up into the piston and the air chamber by means of another flanged packing 26 in the bore. Between such packings the bore 11 is preferably vented. Similar packings 27 and 28 are located in the bore 19 above the chamber 18.

40 Inasmuch as the substance handled by a measuring and dispensing machine of the volumetric type is supplied to the machine in a substantially constant flow, it is desirable, in case the operation of the machine is discontinued for any reason, that the flow of substance be returned to the source again, so as not to build up an excessive pressure in the supply line and interfere with the operation of the mechanism pumping the substance 50 from the source to the machine. To provide for such a condition, the bore 11 in the casing of the governor is provided with an annular passageway 29 which communicates with a pipe 30 leading back to the source of supply. Should the pressure on the substance exceed a certain amount, as when the machine 55 discontinues operation, the piston 12 will be raised in the bore 11 until the passageway 29 is exposed beneath the piston whereupon the substance may flow directly from the passageway 14 into the return pipe 30. The passageway 29 is located well above the point which the bottom of the piston 12 reaches 60 when the reduced portion 22 of the rod 17 comes into register with the passageway 20,

so that the piston 12 will never move upwardly far enough to place the passageway 29 in communication with passageway 14 as long as the machine continues in operation.

I claim:

1. In a measuring and dispensing machine 70 of the volumetric type, a measuring cylinder, means for conducting to the cylinder the substance to be measured, and means associated with said substance-conducting means 75 and controlled by the pressure on the substance therein for automatically preventing the substance in the cylinder from leaving the same until after the pressure on the substance has reached a predetermined amount.

2. In a measuring and dispensing machine 80 of the volumetric type, a measuring cylinder, means for conducting to the cylinder the substance to be measured, means associated with 85 said substance-conducting means and controlled by the pressure on the substance therein for automatically preventing the substance in the cylinder from leaving the same until after the pressure on the substance has reached a predetermined amount, and means 90 for varying the pressure at which the substance will be permitted to leave the cylinder.

3. In a measuring and dispensing machine 95 of the volumetric type, a supply line, an air line having a valve therein which must be open in order to permit operation of the machine, and means in the supply line for holding the valve in the air line closed until the pressure on the substance in the supply line has reached a predetermined amount. 100

4. In a measuring and dispensing machine 105 of the volumetric type, a supply line, an air line having a valve therein which must be open in order to permit operation of the machine, means in the supply line for holding the valve in the air line closed until the pressure on the substance in the supply line has reached a predetermined amount, and means 110 for varying the pressure at which the air line will be opened.

5. In a measuring and dispensing machine 115 of the volumetric type, a governor consisting of a casing having two transverse passageways therein, one for the substance under pressure being dispensed from the machine and the other for a fluid under pressure used to operate the machine, means for closing off the passageway for the operating fluid, and means for rendering said closing means ineffective when the pressure in the passageway 120 for the substance reaches a predetermined amount.

6. In a measuring and dispensing machine 125 of the volumetric type, a governor consisting of a casing having two transverse passageways therein, one for the substance under pressure being dispensed from the machine and the other for a fluid under pressure used to operate the machine, a piston in the casing 130 between said passageways, and a rod on the

5 piston closing off the passageway for the operating fluid and having a reduced portion which is movable by the piston into register with said passageway when the pressure in the passageway reaches a predetermined amount.

7. In a measuring and dispensing machine of the volumetric type, a measuring cylinder, means for conducting to the cylinder the substance to be measured, means for causing measured quantities of the substance to be dispensed from the cylinder, and means associated with said substance-conducting means and controlled by the pressure on the substance therein for automatically preventing operation of said last mentioned means until after the pressure on the substance in the cylinder has reached a predetermined amount.

8. In a measuring and dispensing machine of the volumetric type, a measuring cylinder, means for conducting to the cylinder from a suitable source a substantially continuous supply of the substance to be measured, means for causing measured quantities of the substance to be dispensed from the cylinder, means associated with said substance-conducting means and controlled by the pressure on the substance therein for automatically preventing operation of said last mentioned means until after the pressure on the substance in the cylinder has reached a predetermined amount, and means for automatically preventing the pressure on the substance in the cylinder from materially exceeding such predetermined amount.

In testimony whereof I have hereunto signed my name.

BERTIE S. HARRINGTON.
